UNITED STATES PATENT OFFICE.

GEORGE ARTHUR JONES, OF FARMINGTON, NEW HAMPSHIRE.

RAILWAY-TIE.

SPECIFICATION forming part of Letters Patent No. 246,888, dated September 13, 1881.

Application filed June 13, 1881. (No model.)

To all whom it may concern:

Be it known that I, GEORGE ARTHUR JONES, of Farmington, of the county of Strafford and State of New Hampshire, have invented a new and useful Improvement in Railway-Ties; and I do hereby declare the same to be described in the following specification and represented in the accompanying drawings, of which—

Figure 1 is a top view, Fig. 2 a side elevation, and Fig. 3 a longitudinal section, of a railway-tie provided with my invention. Fig. 4 is a transverse section of it taken through one of the rail-seats, and showing the recesses for reception of the removable flange-block, to be described. Figs. 5, 6, 7, and 8 are views of said block and are hereinafter described.

The tie having my invention is to be of wrought-iron or steel, or of cast-iron, in one piece thereof, it, practically speaking, being a tie and two chairs arranged and combined in one piece of metal.

The nature of my invention is fully defined in the claims hereinafter presented.

In the drawings, A denotes the tie, having near each end of it a flat seat, a, the two seats a a being connected by vertical or parallel flanges b b, which terminate at and extend above the two seats and project above the base portion c of the tie, in manner as represented. These flanges, where next each of the seats, are recessed, as shown at d e, to receive a movable block, B, provided with a flange, f, to project over the inner flange, g, of a rail, C, when extended across the seat. Furthermore, the tie has two flange-overlaps, h, projecting up from it, and directly over and upon the outer flanges of the rail. Each movable flange-block B, formed as shown in top view in Fig. 5, in front elevation in Fig. 6, in end view in Fig. 7, and rear elevation in Fig. 8, extends across the tie and into the recesses d e, made therein for its reception. The recesses and block, formed as represented, admit of the block, on removal of its fastening-screw, being easily raised out of place in the recesses. The space or groove l between the ribs or flanges b b is extended through each of the seats a, and for a short distance underneath and within the two flange-overlaps, as shown, to form recesses u u, there being arranged in each of said recesses u u and in each seat,

and under each flange-overlap and each movable block B, a quadrilateral prism, D, of wood or other suitable yielding material, to constitute what I term a "ligneous cushion" or yielding bearing for the rail to rest on, such cushion crossing the seat and rising somewhat above the same. This cushion is held in place or from slipping back in the recess u by a spike, F, going down through an aperture, s, in the block B, and into or through the cushion, and into or through a hole, m, in the base of the tie, if necessary.

Each block B is confined within its receiving-recesses d e by a screw-bolt, n, going through it and one of the flanges b, and by a nut, o, screwed on such bolt. In the lower part of each block B, and to open through its rear side and bottom, is a notch, p, to receive a "pry," when used to force up the block, in order to draw the spike out of the cushion or piece of wood D. The said pieces of wood constitute yielding supports for the rails, and thereby prevent the injurious results which would follow were the rails to rest directly upon the seats a a.

The rail-tie, constructed, as described, of metal and provided with the removable flange-blocks and the wooden prisms or cushions held in place in it by means as described, is intended to take the place of a common wooden tie, and two separate metallic chairs bolted upon such tie. Possessing the durability of a stone tie, the metallic tie, with its wooden cushions, as described, is free from the objections incident to a stone tie, as it becomes an easier or yielding support for the rails, and is stronger and less liable to become broken, and in case of breakage the material composing it can be recast to form another such tie.

What I claim as my invention is as follows, viz:

1. Each movable flange-block B, provided with the pry-receiving notch p, arranged in it as and for the purpose set forth.

2. The metallic rail-tie having the base c, two flanges, b, seats a, flange-overlaps h, and the recesses u, for reception of the cushions, and the movable flange-blocks, all being substantially as set forth.

3. The movable flange-block B, provided with the aperture s, to receive the spike, and

also with the flange *f*, to project over the rail-flange, as explained.

4. The metallic rail-tie provided with the stationary flange-overlaps *h*, removable flange-blocks *B*, and the cushions or wooden prisms *D*, arranged as described, and also with the cushion-fastening spikes *F*, disposed in such

cushions and flange-blocks, all being substantially as set forth.

GEORGE ARTHUR JONES.
